UNITED STATES PATENT OFFICE.

ALEXANDER MC GUIRE, OF WINSTED, CONNECTICUT.

IMPROVEMENT IN THE MANUFACTURE OF TABLE-CUTLERY.

Specification forming part of Letters Patent No. 43,785, dated August 9, 1864.

To all whom it may concern:

Be it known that I, ALEXANDER MC GUIRE, of Winsted, county of Litchfield, and State of Connecticut, have invented a new and useful Improvement in the Manufacture of Table-Cutlery; and I do hereby declare that the following is a full, clear, and exact description thereof, reference being had to the accompanying drawings, making a part of this specification, in which—

Figure 1 is a side view of a knife in which the blade and tang are made of one piece, and the bolsters applied by welding. Fig. 2 is a sectional view showing nibbed bolsters applied to a table-knife. Fig. 3 is a cross-section taken at the point indicated by red lines *p p*, Figs. 1 and 2. Figs. 4 and 5 are sectional views taken through the swaging-dies during the operation of producing a "nib-bolster." Figs. 6 and 7 show the nib-bolsters ready for use.

Similar letters of reference indicate corresponding parts in the several figures.

The invention which I have made relates to an improvement in the production of those parts of table-cutlery known as "bolsters" or "shoulders," when the same are made separately and afterward applied to the cutlery, as will be hereinafter described.

To enable others skilled in the art to make and use my invention, I will describe its construction and operation.

In the accompanying drawings, Figs. 1, 2, and 3, I have represented a table knife which has its blade and tang formed of one piece of metal, or of two flat pieces of metal welded together at the junction of the blade and tang. At this latter point it is necessary to apply on each side of the tang a bolster or shoulder, against which the forward ends of the handle-sections abut, and which form protections and give a finish to the handle. These bolsters are made separately from the knife blade or tang, when the two latter parts are formed in one piece, as above stated, and then welded in their proper places, which operation renders the production of very good table-cutlery very simple, and greatly diminishes the labor and expense thereof.

When the bolsters *a a'* are made separately, I produce them in the following manner: A represents a swaging-die which has a depression made in its face corresponding in shape and size to that of the nib-bolsters represented

in Figs. 6 and 7; and B represents a die which has a smooth bottom face and a perforation, *b*, through it, or into it, as shown in Figs. 4 and 5, to receive a portion of the metal stock which is forced into said hole during the swaging operation.

To produce the bolsters with nibs on their faces, as represented in Figs. 6 and 7 and in Figs. 2 and 3, a strip of metal of the proper width and thickness is adjusted upon the lower die, A, so that its end will be over the depression in this die. The upper die, containing the perforation *b*, is now forcibly brought down upon the metal, and this metal swaged into the shape corresponding to the depression above described, and the perforation *b* thus producing a bolster having a nib, *c*, projecting from that side of it which is brought in contact with the side of the knife-tang, as shown in Figs. 2 and 3. Thus it will be seen that the nib and bolster are produced at one and the same time by one operation of swaging and of the same piece of metal.

To apply the nib-bolsters which I have just described to a knife of the description represented in Figs. 1 and 2, perforations are made at the proper points through the tang *g*, and the nibs *c* are inserted into these holes in the manner substantially as shown in Fig. 3, after which the bolsters are welded to the knife and then finished up in the usual manner.

The process of making these nib-bolsters I term the "drop process," inasmuch as the nibs are dropped from or produced out of the same stock and during the operation of swaging the bolster, the whole thing being very simple and the nib-bolster very perfect when made.

The nibs *c* may be made near the ends, or in the middle of the bolsters, and they may be made to pass entirely through the tangs, or only partly through.

Having thus described my invention, what I claim as new, and desire to secure by Letters Patent, is—

Forming a nib-bolster for table-cutlery by the drop process, substantially as and for the purposes described.

ALEXANDER MC GUIRE.
